THERMOMETER HOLDER

William M. McGuigan, 5131 Oakview Drive,
Swartz Creek, Mich. 48473

Filed Sept. 26, 1969, Ser. No. 19,312

Term of patent 14 years

Int. Cl. D10—09

U.S. Cl. D52—7

FIG. 1 is a front perspective view of a thermometer holder showing my new design;

FIG. 2 is a view from one side thereof;

FIG. 3 is a view from the opposite side thereof;

FIG. 4 is a top plan view thereof;

FIG. 5 is a bottom plan view thereof;

FIG. 6 is a rear view thereof;

FIG. 7 is a perspective view of the thermometer holder shown in FIG. 1, mounted in an alternate position;

FIG. 8 is a front view thereof; and

FIG. 9 is a fragmentary view of the mid-section of the configuration of FIG. 8 as viewed from the right side of FIG. 7.

I claim:

The ornamental design for a thermometer holder, as shown and described.
